UNITED STATES PATENT OFFICE

THOMAS MUNRO, OF PHILADELPHIA, PENNSYLVANIA

SPRING COVER

Application filed October 4, 1928. Serial No. 310,213.

This invention relates to covers for the springs of motor vehicles, the principal object being the provision of a spring cover which will seal the spring against contact with dust and dirt in a more efficient manner than conventional constructions and which will protect the securing laces from injury.

Another object is to provide a spring cover with dual flaps.

Another object is to provide a spring cover with dual overlapping flaps, each of which is provided with a resilient member at the point of overlapping.

A further object is to provide a spring cover having a pair of flaps adapted to be positioned in overlapping relationship when in operative position upon a spring, and each of the flaps being provided at its margin with a strip of felt or like material providing a resilient pad which serves to maintain the securing laces out of rubbing contact with the spring and aids in preventing the movement of the spring from stretching the laces to their breaking point.

The above being among the objects of the present invention, the same consists in certain features of construction and combinations of parts to be hereinafter described with reference to the accompanying drawing, and then claimed, having the above and other objects in view.

In the accompanying drawing which illustrates a suitable embodiment of the present invention, and in which like numerals refer to like parts throughout the several different views,

Fig. 1 is a fragmentary side view of a vehicle spring provided with a spring cover constructed in accordance with the present invention, the spring cover being shown in section as on the line 1—1 of Fig. 2.

Fig. 2 is a vertical sectional view taken on the line 2—2 of Fig. 1.

Fig. 3 is a partially broken plan view of the spring cover with the flaps thereof turned under as indicated by dotted lines in Fig. 4.

Fig. 4 is a transverse sectional view of the spring cover.

In the ordinary type of spring covers designed to completely enclose the spring when

operatively positioned thereon the cover is provided with a single flap usually of slightly greater width than the space which it is to close and the free edge of which is adapted to be tucked under the opposite free edge of the cover. Because of the width of such flaps and the construction of such covers it is usually a relatively difficult operation to put the flap in place so as to result in a neat-appearing job. Furthermore, in conventional constructions, no positive means except that of drawing the cover against the overlapped portion of the flap is provided for sealing the cover between the free edge of the flap and the corresponding edge of the cover. In addition, in spring covers which employ a lacing for securing them in place upon a spring, the construction is such that the lacing bears against the spring with one layer of cover fabric and not more than one layer of felt interposed between them, with the result that constant deflection of the spring causes the lacing to rub against the cover and often stretches it to the breaking point.

The present invention contemplates the elimination of the difficulties experienced in connection with conventional constructions, as above pointed out, by the provision of a pair of flaps for each spring cover, and the free edges of which are adapted to overlap when applied to the spring. This results in flaps of less width than in conventional constructions and which overlap substantially on the center line of the spring, which thereby makes it a comparatively simple job to properly position the flaps with respect to each other when assembling the cover to a spring. Furthermore, I secure along the free edge of each flap a strip of felt or like material which serves to effect a double seal for the cover against the entrance of dust and dirt and leakage of lubricant, and further provides a double thickness of such felt against which the lacings bear and which thus serves as a padding to protect them from damage due to rubbing or stretching of the lacings.

Referring to the drawings, in Figs. 1 and 2 is shown a vehicle spring 10 of the conventional multiple leaf type. The spring 10 is provided with a cover which may be made of

fabric or other suitable material treated so as to be impervious to lubricant and formed to provide a central portion 11 and side portions 12, the fabric between such portions preferably being reversely bent at 13 and sewed together along such portions except in the immediate neighborhood of the spring clips 14 and 15 so that such reversely bent portions may pull apart at such clips and thereby form a pocket in which the clips are received. The portions 11 and 12 may be lined with a suitable lubricant-absorbing material such as felt, if desired, but in the construction shown the ends only are provided with strips 16 and 17 of such material which serve to seal the cover at such ends against the escape of lubricant and against the entrance of dust or dirt.

In accordance with the present invention the free edges of the side portions 12 are each provided with a flap 18 which may be sewed as shown or otherwise suitably secured thereto. The flaps 18 are adapted to extend under the bottom face of the spring 10 with their free edges positioned in overlapping relationship with respect to each other as indicated in Figs. 1 and 2. The margin of each of the flaps 18 is provided with a strip 19 of felt or other suitable material of like qualities, the strips 19 being of an appreciable width and lying in overlapping relationship with respect to each other when the cover is in assembled position. The free edges of the side portions 12 are provided with a plurality of fastener members 20 between which is strung a lacing 21 which serves to draw the cover into intimate contact with the spring 10 and hold the flaps 18 in their proper relative positions.

It will thus be seen from the foregoing that the joint between the flaps 18 is protected from the escape of lubricant from within the cover and from the entrance of dust and dirt into the cover by a double seal of material 19, and that the lacing 21 extends over and is protected from rubbing by a double thickness of material 19 which forms a resilient pad for the lacing that will give when the lacing is stretched. It will also be apparent that by employing the double flaps they may be assembled to the spring in their proper relationship so as to form a neat-appearing finished product on the spring much more easily than if a single flap of greater width was provided in which the free end was intended to be tucked up between one of the cover sides and the corresponding side of the spring 10.

As previously pointed out it is immaterial to the practice of the present invention whether or not the cover is lined with a suitable lubricant-absorbing material, and it will be further evident that it is immaterial to the practice of the present invention whether or not the entire spring cover is made from a single piece of material or from a plurality of pieces suitably secured together, and these

and other formal changes may be made in the specific embodiment of the invention described without departing from the spirit or substance of the broad invention, the scope of which is commensurate with the appended claims. 70

What I claim is:

1. A spring cover comprising a main body portion adapted to enclose three sides of a vehicle spring, a flap secured to each free side edge of said main body portion, said flaps adapted to overlap over the remaining side of said spring, and a strip of cushioning material secured to each of said flaps along the line where it overlaps the other of said flaps. 75

2. A spring cover comprising a unitary member adapted to enclose a spring and having free side edges adapted to overlap on one face of said spring, said member being provided with strips of lubricant absorbing material secured along and commensurate in length with all of the free edges thereof, said strips on the free side edges of said member lying in overlapping relationship when in assembled position upon a spring. 80

3. In combination with a vehicle spring, a cover comprising a main body portion adapted to cover three sides of said spring, lace engaging means along the free side edges of said main body portion, a flap secured to each free side edge of said main body portion, said flaps adapted to cover the fourth side of said spring and overlap each other along their free side edges, said flaps each being provided with a strip of cushioning material along their line of overlap, and a lace strung between said engaging means for securing said cover to said spring, the double thickness of said cushioning material forming a protective padding for said lace. 95

4. A spring cover comprising a main body portion adapted to enclose a vehicle spring and overlapping along the length of one face of said spring, a strip of cushioning material being secured to each free edge of said body portion along said line of overlap whereby to effect an area of double the combined thickness of said body portion and one of said strips. 100
